Primary Examiner—Alan P. Douglas*Assistant Examiner*—Lavone D. Tabor**[57] CLAIM**

The ornamental design for a high density electrical connector, as shown.

DESCRIPTION

FIG. 1 is a perspective view of a high density electrical connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

FIG.1

FIG.2

FIG.3

FIG.4

FIG. 5

FIG.6

FIG. 7
